UNITED STATES PATENT OFFICE.

WILLIAM B. FULTON, OF MIDDLETOWN, OHIO.

HEATING AND DRYING APPARATUS.

Application filed May 6, 1921. Serial No. 467,343.

To all whom it may concern:

Be it known that I, WILLIAM B. FULTON, a citizen of the United States, and resident of Middletown, county of Butler, and State 5 of Ohio, have invented certain new and useful Improvements in Heating and Drying Apparatus, of which the following is a full, clear, concise, and exact description, reference being had to the accompanying drawings, forming a part of this specification.

The present invention relates to drying apparatus to be used in the process of manufacturing paper or textiles. Such an apparatus usually consists of a plurality of 15 rolls or other driers heated by steam and the web of material is caused to pass over the successive driers in contact with their heated surfaces. It is desirable to arrange the driers in groups and to maintain a difference in steam or vapor pressure in the 20 driers of the different groups. The first group of driers over which the web of material passes is commonly called the "wet end" of the machine and this group of driers 25 is referred to herein as the primary group. The other group of driers is commonly called the "dry end" of the machine and this group of driers is referred to as the secondary group. I have illustrated the invention 30 as applied to a machine including only primary and secondary groups although it will be understood that the machine may be enlarged if desired by the addition of further groups of driers.

It is an object of the present invention to 35 provide a drying apparatus in which the driers may be heated efficiently by steam or other vapor and in which a difference in pressure may be maintained between the 40 driers of successive groups. It is also an object of the invention to provide an apparatus of this kind which may be located partly in a basement or other limited space, and it is a further object of the invention to 45 provide means for efficiently relieving the apparatus of air and water of condensation.

In the drawings,—

Figure 1 is a side view of the apparatus, certain parts being shown in section, 50 Figure 2 is a view partly in section and partly in elevation of one of the driers and associated parts.

The web of material is presumed to be 55 passing over the drier from right to left in Figure 1. The plurality of driers 7 disposed to the right of the valve 45, constitute the

primary group of driers or the "wet end" of the machine. The succeeding driers 8 constitute the secondary group of driers. The supply pipe 10 leads from a supply of steam 60 under pressure and is connected by branches 11 with each of the driers 8 of the secondary group. Each drier is provided with a pipe 13 opening from the lower part of the drier and extending through the hollow trunnion 65 12 to a branch communicating with the discharge pipe 15. It will be understood that the hollow trunnion 12 is so constructed as to permit the inlet of steam from the branch 11 and the egress of steam, air and water of 70 condensation through the pipe 13 to the pipe 15, while at the same time permitting rotation of the drier 8. An illustrative example of such a trunnion and connection is shown in my Patent No. 1,380,373 issued June 17, 75 1921.

In heating the driers 8 of the secondary group, the steam becomes reduced in pressure and with the air and water of condensation passes out through the pipes 13 and 80 their connected branches into the manifold 15. A receiver 16 receives the discharge from the manifold 15 and in the drawing the receiver is illustrated as located in cramped space and extending above the manifold 15 85 and the lower part of the lower tier of driers of the secondary group. From a low point of the manifold 15 a pipe 17 leads into a lower part of the receiver 16 while a connection 18 is made from the manifold 15 to 90 the upper part of the receiver. Water of condensation enters the receiver through the pipe 17 and is ultimately discharged as will be described. Steam and air enter the upper part of the receiver through the connection 18. The steam and air are forced to pass 95 down under a baffle 20 in the receiver to the outlet 19, with which is connected a pipe 21 communicating with a pipe 22. The pipe 22 is provided with branches 23 conducting the lowered pressure steam to the driers 7 of 100 the primary group, while each drier 7 is also provided with a discharge pipe 25 leading to the discharge manifold 27. The driers 7 are provided with trunnions similar to 105 those of the driers 8. It is important to the economical operation of the system that the discharge of steam from the primary driers be restricted and this may be accomplished by the provision of steam traps 24 interposed in the respective discharge branches 25. A by-pass 35 is provided around each

of the steam traps. Each by-pass has a valve 36 normally restricted but which may be fully opened at the commencement of operation to secure circulation of steam through the various elements of the system. The air and water of condensation discharged from the primary driers into the manifold 27 passes through the pipe 28 and the check valve 29 into the trap 30. The trap 30 is provided with a float 31 and when the collected water reaches a pre-determined level the float through valve mechanism 32 operates to open valve 33 in a steam line 34 whereby steam is admitted to carry the collected water to a boiler or other reservoir through the pipe 34. To prevent the system from becoming "air-bound" an air vent 40 is connected with the pipe 28 between the trap 30 and the individual steam traps with which the primary driers are equipped.

In order to discharge from the receiver 16 water of condensation drained from the secondary driers I provide mechanism 41 arranged to operate when the water in the receiver reaches a pre-determined level so as to open the receiver to the discharge pipe 43. Thereupon, the steam pressure in the receiver forces the water out of the receiver through the discharge pipe 43. The amount of water collected in the receiver may be observed on the gauge 16.

The pipe 10 from which the driers of the secondary group are supplied with high pressure steam communicates with the pipe 22 from which the driers of the primary group are supplied with low pressure steam which has been exhausted from the secondary driers. The communication between the pipes 10 and 22, however, is controlled by the valve 45 which may be entirely closed to prevent communication between the two pipes or which may be regulated so as to maintain the pressure in the driers of the primary group at any desired difference below that in the secondary group. It is important that a desired pressure differential be maintained between the secondary and primary driers in order that the primary driers may operate efficiently, while at the same time the water of condensation may be discharged from the secondary driers. It would be practically impossible so to design the piping of the system as always to maintain this desired differential and in the operation of the system various causes may alter the relations between the pressures in the two groups. By regulation of the valve 45, however, communication between the high pressure pipe 10 and the pipe 22 may be accurately controlled so as to restore and maintain the desired differential between the pressures in the secondary and primary groups. At the commencement of operations the valve 45 should be entirely closed so as to blow air and water from the sec-

ondary driers into the receiver 16. The water will be collected in the receiver while the air will be blown out into the pipe 22 and may be discharged by temporarily opening the valve 50.

Having thus described my invention, what I claim as new and desire to secure by Letters Patent of the United States, is:—

1. A drier system, comprising a primary group of driers, a secondary group of driers, means for supplying steam under pressure to the secondary group, means for discharging water of condensation from the secondary group and for conducting steam and air from the secondary group to the primary group, and a valve for maintaining a difference in steam pressure between the secondary group and the primary group.

2. A drier system, comprising a primary group of driers, a secondary group of driers, means for supplying steam under pressure to the secondary group, means for discharging water of condensation from the secondary group and for conducting steam and air from the secondary group to the primary group, and an adjustable regulator for admitting steam from the means for supplying the secondary group directly to the primary group.

3. A drier system, comprising a primary group of driers, a secondary group of driers, means for supplying steam under pressure to the secondary group, means for discharging water of condensation from the secondary group and for conducting steam and air from the secondary group to the primary group, an adjustable regulator for admitting steam from the means for supplying the secondary group directly to the primary group, means for discharging air and water of condensation from the primary group, and means for restricting the escape of steam from the primary group.

4. A drier system, comprising a primary group of driers, a secondary group of driers, a pipe connected with a supply of steam under pressure, connections from said pipe to the secondary group, connections from said pipe to the primary group, an adjustable valve in said pipe between the connections to the secondary group and the connections to the primary group to maintain a desired difference in pressure therein, and means for discharging water of condensation from the secondary group and for conducting steam and air from the secondary group to the primary group.

5. A drier system, comprising a primary group of driers, a secondary group of driers, a pipe connected with a supply of steam under pressure, connections from said pipe to the secondary group, connections from said pipe to the primary group, an adjustable regulator in said pipe between the connections to the secondary group and the

nections to the primary group, means for discharging water of condensation from the secondary group and for conducting steam and air from the secondary group to the primary group, means for discharging air and water of condensation from the primary group, and means for restricting the escape of steam from the primary group.

6. A drier system, comprising a primary group of driers, a secondary group of driers, means for supplying steam under pressure to the secondary group, a pipe for discharging steam, air and water of condensation from the secondary group, a receiver extending above said pipe, a connection from said pipe to the upper part of the receiver, a connection from said pipe to a lower part of said receiver, and a pipe extending from the upper part of the receiver and communicating with the primary group.

7. A drier system, comprising a primary group of driers, a secondary group of driers, means for supplying steam under pressure to the secondary group, a pipe for discharging steam, air and water of condensation from the secondary group, a receiver extending above said pipe, a connection from said pipe to the upper part of the receiver, a connection from said pipe to a lower part of said receiver, a pipe extending from the upper part of the receiver and communicating with the primary group, means for discharging air and water of condensation from the primary group, and means for restricting the escape of steam from the primary group.

8. A drier system, comprising a primary group of driers, a secondary group of driers, means for supplying steam under pressure to the secondary group, a pipe for discharging steam, air and water of condensation from the secondary group, a receiver extending above said pipe, a connection from said pipe to the upper part of the receiver, a connection from said pipe to a lower part of said receiver, a pipe extending from the upper part of the receiver and communicating with the primary group, and an adjustable regulator for admitting steam from the means for supplying the secondary group directly to the primary group.

9. A drier system, comprising a primary group of driers, a secondary group of driers, means for supplying steam under pressure to the secondary group, a pipe for discharging steam, air and water of condensation from the secondary group, a receiver extending above said pipe, a connection from said pipe to the upper part of the receiver, a connection from said pipe to a lower part of said receiver, a pipe extending from the upper part of the receiver and communicating with the primary group, means for discharging air and water of condensation from the primary group, means for restrict-

ing the escape of steam from the primary group, and an adjustable regulator for admitting steam from the means for supplying the secondary group directly to the primary group.

10. A drier system, comprising a primary group of driers, a secondary group of driers, a pipe connected with a supply of steam under pressure, connections from said pipe to the secondary group, connections from said pipe to the primary group, an adjustable regulator in said pipe between the connections to the secondary group and the connections to the primary group, a pipe for discharging steam, air and water of condensation from the secondary group, a receiver extending above said pipe, a connection from said pipe to the upper part of the receiver, a connection from said pipe to a lower part of the receiver, and a pipe extending from the upper part of the receiver and communicating with the primary group.

11. A drier system, comprising a primary group of driers, a secondary group of driers, a pipe connected with a supply of steam under pressure, connections from said pipe to the secondary group, connections from said pipe to the primary group, an adjustable regulator in said pipe between the connections to the secondary group and the connections to the primary group, a pipe for discharging steam, air and water of condensation from the secondary group, a receiver extending above said pipe, a connection from said pipe to the upper part of the receiver, a connection from said pipe to a lower part of the receiver, a pipe extending from the upper part of the receiver and communicating with the primary group, a trap for discharging water of condensation from the primary group, means for restricting the escape of steam from the primary group, and an air vent between said trap and said restricting means.

12. A drier system, comprising a primary group of driers, a secondary group of driers, means for supplying steam under pressure to the secondary group, means for discharging water of condensation from the secondary group and for conducting steam and air from the secondary group to the primary group, and a valve so located that steam is supplied to all of the secondary driers before it reaches said valve and that it controls the pressure of the steam passing to all of the driers of the primary group, thus being adapted to maintain a difference in pressure between the secondary group and the primary group.

13. A drier system, comprising a primary group of driers, a secondary group of driers, means for supplying steam under pressure to the secondary group, means for discharging water of condensation from the

secondary group and for conducting steam and air from the secondary group to the primary group, a receiver connected to said means, and a valve so located that steam is supplied to all of the secondary driers before it reaches said valve and that it controls the pressure of the steam passing to all of the driers of the primary group, thus being adapted to maintain a difference in

pressure between the secondary group and the primary group.

In witness whereof, I hereunto subscribe my name this 30th day of April, 1921.

WM. B. FULTON.
